UNITED STATES PATENT OFFICE.

HERMAN A. AGRICOLA, JR., OF ATLANTA, GEORGIA, ASSIGNOR OF FORTY-NINE ONE-HUNDREDTHS TO JOSEPH E. LANE, OF ATLANTA, GEORGIA.

PRINTING-PRESS ATTACHMENT.

Application filed May 3, 1923. Serial No. 636,371.

To all whom it may concern:

Be it known that I, HERMAN A. AGRICOLA, Jr., a citizen of the United States, residing at Atlanta, in the county of Fulton and 5 State of Georgia, have invented certain new and useful Improvements in Printing-Press Attachments, of which the following is a specification.

The present invention has reference to 10 printing presses having multi-color attachments of the general kind set forth in my applications, Serial Nos. 420,627 and 527,574, filed, respectively, October 30, 1920, and January 7, 1922, Patent Nos. 15 1,481,495 and 1,503,222, respectively.

The features constituting my invention are designed for embodiment in one or more units which may be conveniently attached to presses of standard type so as to adapt 20 them to perform chromatic printing. This invention effects the above results by the employment of a reciprocating carriage which supports the inking, transferring and printing rollers the rotation whereof 25 results from the use of a rack and an intermeshing train of gears which drive the rollers with each reciprocation of the carriage; and also by the employment of an inking 30 plate in which are assembled a plurality of pinions provided with means for effecting intermittent rotation thereof, when desired, the several pinions being disposed flush with the working face of the plate so as to 35 operate therewith in distributing ink of one or more colors over certain selected rollers, or portions thereof. The invention consists further in numerous other features of construction and combinations of parts as will more clearly hereinafter appear from the 40 specification and claims, taken in conjunction with the accompanying drawings, wherein the present improvements are illustrated in the manner following:

Figure 1 is a side elevation of the upper 45 portion of a conventional printing press showing the carriage attachment in its elevated position;

Fig. 2 is a front elevation of the same 50 showing the chase with a plurality of individual type sections carried therein;

Fig. 3 is an elevation of the rear side of the carriage containing the several inking, transferring and printing rollers;

Fig. 4 is a horizontal section through the press frame, together with chase thereon, 55 and also through the carriage, taken on line 4-4 of Fig. 3;

Fig. 5 is a vertical section through the carriage and inking plate, the plane of the section being line 5-5 of Fig. 3; 60

Fig. 6 is a similar view showing the carriage in a lowered position;

Fig. 7 is a fragmentary view in elevation of certain of the parts shown in Fig. 6;

Fig. 8 is a transverse section taken on line 65 8-8 of Fig. 7;

Fig. 9 is a vertical section through the carriage taken on line 9-9 of Fig. 4;

Fig. 10 is a view in elevation of the working face of the inking plate showing one adjustment of the several pinions incorporated 70 in its structure;

Fig. 11 is a similar view showing another adjustment of its pinions;

Fig. 12 is a sectional view taken on line 75 12-12 of Fig. 11;

Fig. 13 is a view in elevation of the rear side of the inking plate;

Fig. 14 is a fragmentary detail, enlarged, showing a modified construction wherein the 80 inking fountain is stationary;

Fig. 15 is a sectional view on line 15-15 of Fig. 14;

Figs. 16 to 19 inclusive are views in elevation of the ink plate and chase frame 85 showing four different arrangements of inking pinions and type sections so as to produce in each instance a different printing result;

Figs. 20 to 22 inclusive are diagrammatic 90 views showing in transverse section a carriage which is equipped with a modified form of latch, together with an automatic release therefor, three positions being indicated; and

Fig. 23 is a front elevation of the carriage having the modified structure shown in the previous figures.

The attachment of this invention is applicable to printing presses of different 100

kinds, such, for instance, as rotary, flat bed, etc. For purposes of exemplification, I have represented in Figs. 1 and 2 a job press 5 pivoted to oscillate about a horizontal axis through the medium of a pitman B which derives motion from a suitable power source.

Mounted on the press are the usual rocker arms C arranged to oscillate about an axis D, the means for effecting such oscillations 10 being of any suitable kind. These arms C which lie upon opposite sides of the press are connected as by means of a plate E on which is carried a pair of brackets F for pivotally supporting two links G which are 15 adjustably connected as at H with rocker arms I pivoted at J to swing upon a suitable bracket or support K. At the end of each rocker arm opposite the connection H is a pivotal connection L with an arm M to 20 which is secured a turn-buckle N which also connects with another arm section O. The parts thus connected are adapted to reciprocate upon the forward side of the press a carriage P whose construction in detail will 25 presently be described. In the kind of press shown, the carriage moves in a straight line wholly upon the front of the press, but the carriage may take other courses of travel such, for instance, as circular or angular, or, 30 as in the case of a rotary press, relative movement may obtain with the carriage remaining stationary.

Referring now to Fig. 3, the carriage frame is shown as comprising end plates 35 and 21 between the opposite extremities of which are extended top and bottom rails 22 and 23, respectively. Each end plate is formed with a pair of slots 24 which proceed inwardly from the forward side of the 40 carriage for an appreciable distance, and then downwardly to provide bearings for two shafts 25 and 26 which are disposed one above the other, as best shown in Fig. 9. The ends of these shafts are further 45 journaled in plates 27 of which there are four, each plate having a pin 28 which is received within a socket formed within the outer side of the proximate end plate 20 and 21, and being bolted or otherwise secured 50 thereto (see Fig. 1). In some such manner as this the two shafts may be securely mounted within the carriage in a manner which permits of their convenient assembly or disassembly relative thereto.

55 The end plates of the carriage extend rearwardly so as to lap past the sides of the press bed (see Fig. 4) whereon are mounted a pair of guide bars, one 30 arranged forwardly of the other 31, these bars being disposed in the direction of travel which it is 60 designed the carriage should take. Between these bars is a space in which is slidingly received a co-operating guide block 32 one of which is mounted on a rearward extension at each end of the carriage. By the

means suggested the carriage is adapted to be guided in reciprocating movements across the front of the press bed, being held always to the line of travel that is predetermined by the positioning of the several guide bars.

70 The two shafts 25 and 26 which may be journaled in the carriage in the manner described each serves as a mounting for a duplex roller system the components of each being designed to execute a limited swinging movement during travel of the carriage. Each roller system constitutes a unit in itself which is independent of the other, although practically a duplicate thereof. Accordingly a description of only one roller system will follow, the understanding being that the same description and reference numerals will apply to the other system also.

75 Adjacent the inner side of each end plate 20 and 21 is a bearing plate 36 and 35, respectively, these plates having openings through which are extended the shafts 25 and 26 so as to be swingingly supported thereby. Inasmuch as four such bearing plates are employed, two for each shaft, it follows that their arrangement is such as to provide suitable mountings for certain rollers which may be positioned horizontally across the carriage. Associated with each bearing plate is a stop member 37 and also a spring member 38, these two sets of members being shown as secured, respectively, to the inner sides and forward edges of the carriage and plates 20 and 21 (see Figs. 3 80 and 9). The spring members are each arranged to exert pressure upon a lug 39 which projects laterally from each bearing plate 35 and 36 so as to normally maintain the same against the stop member in a position such as is indicated in Fig. 9.

85 The various rollers which are mounted between the bearing plates 35 and 36 each include a shaft, there being four such shafts, numbered 40 to 43 inclusive, additional to the supporting shafts 25 or 26. The shafts 40 and 41 lie one below the other and below the supporting shaft in a substantially straight line; the shaft 42 lies forwardly of shafts 40 and 41 and equidistantly therefrom; while the shaft 43 is disposed forwardly of the others, and, equidistant with shaft 41, from shaft 42. A train of pinions, all of which may be of the same size, are employed to connect up these several shafts 90 for a common drive, and for this purpose use is made of five pinions, numbered 44 to 48 inclusive, which are mounted fast on the supporting shaft and remaining shafts 40 to 43 inclusive, respectively.

95 As indicated in Figs. 3 and 4, these several pinions lie in slightly spaced relation to the bearing plate 35. Within each of these spaces at one end of the carriage is received a second bearing plate 50, a complementary plate 51 being also provided at 100

the opposite carriage end where, it will be noted, no pinions are required. These second bearing plates also are supported on the shafts 25 and 26 in exactly the same manner as the previously described plates 35 and 36, so as to have capacity for a limited swinging movement about the same axis.

Mounted on the bearing plate 50 is a stub shaft 52 on which is fastened a pinion 53 which may be somewhat larger than the remainder in the drive for the roller system; also between the bearing plates 50 and 51 is extended a roller shaft 54 whereon is received a pinion 55 in mesh with the pinion 53 which also is meshed with the pinion 44, this latter pinion being adapted to drive the train that is carried by the other bearing plates 35 and 36. There is thus provided a duplex roller system having a common drive, each component of the system being mounted co-axially to swing independently of the other. Reference should be had to Figs. 3 and 5 where it appears that the pinions 48 are not aligned with the proximate pinions 55 in the other component of the same system, although an opposite impression might be gained from Fig. 9. By locating the pinions 48 to one side of the others, and also laterally extending the meshing pinion 47, as shown, it is possible to connect up the several shafts in the manner described so that each component of the system is driven only through one common pinion, viz., 44.

To effect rotation of the several shafts heretofore described, use is made of one further pinion 56 for each roller system, these being mounted on the inner side of the carriage end plate 21 in meshing relation in each instance with the pinion 44 and with the teeth of a rack 57 which is provided upon the forward edge of the proximate guide bar 30. With such an arrangement, each reciprocation of the carriage will cause a rotation of the two pinions 56 together with all the others in the several trains connected therewith, with the result that each component of both roller systems will be subjected to positive rotative movements.

Referring now to Fig. 3, it will be noted that all of the shafts, with the exception of those numbered 25, 26 and 52, are built up throughout their central positions to provide rollers which are suitable for receiving, transferring, or printing ink. This may be accomplished in any of the well known manners, as, for example, by the use of a rubber composition which is formed to the desired length and diameter. The section of Fig. 5 suggests how these several rollers are interrelated, it being requisite for the purpose of this invention that they be interengaged so as to effect a proper transfer of ink. Those rollers which, for con-

venience, are termed "printing rollers" are mounted on shafts 40 and 41 and operate to ink the form; shafts 42 carry a roller in engagement with both printing rollers and with a further roller on shaft 43; and this last roller which underlies an inking roller on shaft 54 is adapted to transfer ink therefrom to the others. For purposes of convenience the several rollers just named are designated by reference numerals the same as those applied to their respective shafts.

The shaft 54 whereon each inking roller is carried is broken near one end, its two sections being provided with a one-way driving connection, as best shown in Figs. 3 and 7. By preference this comprises a pair of co-related clutch heads 60 and 61, having engaging faces formed with circular ratchets 62 and 63, respectively. The head 60 is fixedly secured to one section of the shaft while the other head is slidably, but non-rotatably, carried on the other shaft section. A spring 64 which bears against the sliding head operates to maintain this part yieldingly against the other head with the result that a one-way driving connection is at all times maintained. To properly support one shaft section with respect to the other, their meeting ends are preferably telescopingly related.

The two shafts 41 are further provided each with a pair of wheels 65 and 66 (see Figs. 3 and 4) those on one shaft being spaced apart slightly further than those on the other. For each pair of wheels so arranged, there is provided a pair of cam tracks 67 and 68 (see Fig. 2) which are secured on the front face of the chase frame 69, the mounting for which is, as usual, upon the front of the press bed. The tracks 67 which are offset with respect to the others extend for perhaps half the vertical length of the chase frame, while the other tracks 68 extend for the balance of its length. According to this arrangement one pair of wheels, say 65, will ride up and along one set of rails during a portion of the carriage travel, the other pair of wheels, say 66, thereafter riding up and along the other set of rails during the balance of the carriage travel. As these rails stand out slightly from the chase frame whereon the wheels are adapted normally to bear, it follows that any engagement of the wheels with the rails will cause the latter to be outwardly displaced. When this occurs the entire associated roller system will be swung around its supporting shaft as an axis, from the position occupied by the upper roller system in Fig. 6, for example, to that which is shown for the lower roller system in the same figure where, it will be observed, the printing rollers are removed from contact with the form. These movements of the wheels on and off the rails are facilitated by

suitably rounding the ends of the latter, as indicated in Figs. 2 and 6. The effect of the carriage movements, therefore, will be to swing outwardly first one roller system 5 for one portion of its travel across the form, and then the other system for another portion of its travel across the form, the printing rollers of each system being thereby held successively in contact with the form at all 10 other points. In other words, the construction heretofore described is such as to assure a successive contact for the printing rollers in the two systems with only predetermined portions of the form.

15 In connection with each roller system, I provide means also for delivering a controlled supply of ink in one or more colors, to the printing rollers. This part of my invention is set forth most clearly in Figs. 5 and 20 6. As shown, it comprises a pair of trough-shaped members each formed of two angularly related walls 70 and 71, the former presenting one edge closely adjacent the inking roller 54, and extending inwardly 25 and upwardly away therefrom to connect with the other wall which overhangs this roller. In addition, the face of the wall 70 which lies proximate to the other is preferably concave, as at 72, a flexible spring 30 blade 73 being extended thereover with one of its edges lodged within the corner formed by the intersection of these two walls. The other blade edge, designated as 74, lies closely adjacent the inking roller 54, and, in 35 fact, may engage therewith when the blade lies straight or substantially so. If, however, the blade be displaced so that its body is forced into the concavity of the wall 70, its edge 74 will recede slightly from the 40 inking roller, as indicated in Fig. 5. For accomplishing such a result, I provide a cam 75 adapted to move against the upper side of the blade, this cam being fixed to a stem 76 which is rotatably mounted in the overhanging wall 71. At its upper end which is shown as extending through the wall is formed a laterally bent finger 77 to afford a convenient means for rotating the stem and cam by which the blade may be adjusted to the curved position desired. It 45 is contemplated that a supply of ink may be deposited on each blade, a different color of ink over each, if desired, so as to feed therefrom to separate end portions of the inking roller, but that by some means as 50 has been described a control may be exercised over the transfer of each such ink to the roller system.

60 This transfer of ink to the remaining rollers is subject to control by the operator as by the following means. Mounted on the slidable head 61 is a collar 80 having a cam face 81 on one of its sides. Associated with this collar cam is a pin 82 65 slidably mounted in a bar 83 which is ex-

tended across the carriage front with the bar ends suitably supported on brackets 84 that are affixed to the bearing plates 50 and 51. An expansion spring 85 is interposed between the bar 83 and a head 86 formed 70 on the upper pin end adapted normally to maintain the pin in an upper position with its head relatively close to the top carriage rail 22 in the case of the upper roller system, and in the case of the lower system 75 adjacent a shelf 87 which is extended laterally from the carriage end 21. As long as the parts are permitted to occupy the relative positions just indicated, the lower pin end will lie clear of the collar cam.

80 This relationship may not continue for long, however, because the shaft 43 carries an eccentric or cam 90 which is adapted to bear against both heads 60 and 61 to elevate the inking roller 54 and thereby break contact thereof with the transfer roller 43, this elevation occurring during rotation of the eccentric through the upper portion of its movement. This upward displacement of the inking roller also brings the collar cam into engaging relation with the lower end of the pin 82 in consequence of which the slidable clutch head 61 is laterally shifted against the tension of the spring 64 so as to 85 break the driving connection for the inking roller which is mounted on shaft 54. Accordingly this roller alone remains stationary while the remainder of the roller system continues to function. It is to be observed also that with each upward movement of the eccentric, the inking roller not only is elevated, but also the associated parts which are carried between the bearing plates 50 and 51. For this reason the pin head 80 is 90 also brought into contact with the under side of the rail 22, or shelf 87, and forced down against the tension of the spring 85 so as to accelerate the movement of the pin into engaging position with the collar cam.

95 Auxiliary means are further employed for suspending the inking roller in an upper, non-rotative, position as long as desired, and, as shown, this consists of certain latch members, one in the form of a spring-plate 100 having a hook edge 96 adapted to engage the top carriage rail 22 (see Figs. 3, 5, and 6). Such a latch, in the case of the upper roller system, may be attached to any convenient part which is associated with the inking roller unit, as, for example, the overhanging wall 71. In the case of the lower system, two such latch springs are suggested, each in the form of an elongated strap 105 97, the lower end of which may connect with a bushing 98 surrounding the proximate extremity of the shaft 54, the strap extending upwardly therefrom and behind a plate 99 projecting laterally from the carriage end so that its hook end 100 will tend 110 to engage the top carriage rail 22 when the 115

parts are raised sufficiently for this purpose. In this manner the inking roller of each system will be suspended indefinitely after any movement of the eccentric through 5 the upper portion of its cycle, the duration of this suspension being under the control of the attendant who may employ any desired means for a simultaneous release of all the spring latches. Upon any such release 10 the inking roller drops down, and, the clutch 61 being freed from the pin 82, the two end sections of shaft 54 are again locked in driving relation for a brief interval. A suggestive automatic release for the spring 15 latches is shown in Figs. 20 to 23 inclusive, and will be described in detail hereinafter.

The preceding description covers fully the carriage and its roller systems which, as a unit, is adaptable to printing presses of conventional design. Further advantages inherent in the present invention may be realized by the conjoint use also of an inking plate assembly of special construction. This is illustrated in detail in Figs. 5, and 10 to 13 25 inclusive.

As shown, the plate assembly comprises two rectangular base plates 105 and 106 each adapted to extend across the front of the press and be secured thereto adjacent the 30 form. These base plates are connected adjustably to each other by means of a pair of end rails 107, wherein are formed elongated openings 108 through each of which is extended the shank of a bolt 109 which fastens 35 to one end of one of the base plates, the head bearing with pressure upon the rail. In this manner the two plates are held in unitary relation but with capacity for a limited adjustment toward or from each other. The 40 connecting rails are preferably located upon the front side of the base plates as are also four smaller pinion plates 110 to 113 inclusive, each of these plates being rectangular, of equal size, and arranged in pairs so as to 45 cover areas which extend from a vertical line drawn through the middle of each base plate to a line which lies close to the connecting end rails. In this manner each pair of pinion plates may be adjusted toward 50 and from each other within certain limits.

Formed on each pinion plate is a recess on its forward face of a size and shape to receive two meshing pinions 115 and 116, these recesses being open upon the side and end 55 of the plate which lie proximate to the adjacent plate. As appears clearly from Figs. 10 and 11, the general shape of each recess so formed is such as which would be produced by two circles slightly intersecting. 60 The two pinions so disposed within each recess are adapted to present their teeth closely adjacent the marginal walls thereof, and, where margins are lacking so as to provide open spaces, the teeth protrude therethrough. In this manner all of the pinions

may be connected up in driving relation, when all of the pinion plates are interengaged, as represented in Fig. 10. In other positions of adjustment the two pinions in each plate may be so disconnected from the 70 pinions in the remaining plates as to revolve with entire independence (see Figs. 11 and 16) or be meshed with those in either of the adjacent plates (see Figs. 18 and 19).

As represented best in Fig. 12, each pinion is loosely mounted upon a stub shaft 117 extending rearwardly and formed with an annular shoulder 118 adapted to maintain the rear face of the pinion in slightly spaced relation from the recessed plate wherein it is accommodated. The stub shaft which extends rearwardly from the pinion is adapted to revolve within an opening 119 formed in the pinion plate, and extends rearwardly thereof to lie within an elongated slot 120 which is formed in the proximate base plate 105 or 106. Those pinions 116 which lie to the inside of the plate assembly are each secured in place with the aid of a flange plate 121 which overlies the openings 120, a bolt 122 bearing with its head 123 against this flange plate when its shank is entered therethrough to be screwed into the stub shaft. A pin 124 may be used to prevent 95 rotation of the flange plate relative to the stub shaft. By the means described, it is possible to tighten the bolt 122 upon the flange plate 121, the result being that the stub shaft is clamped in place in a given position of adjustment longitudinally of the slotted opening 120. Inasmuch as the shoulder 118 bears against the front side of the pinion plate, it takes up the thrust occasioned by the bolt 122, and so leaves its 100 associated pinion free to revolve.

The four central pinions 116 may each be mounted in place by means such as have been suggested. The four pinions 115 which occupy end positions, however, are each provided with a rearwardly extending stub shaft of slightly greater length, so as to afford a fast mounting for a ratchet wheel 125, also for an arm 126 which is loosely mounted thereon, the two arms occupying uppermost positions being each formed with 110 a rearward extension 127, as shown. A bolt 128 whose head bears upon a flange 129 is adapted to lock the arm and pinion in place. Additionally each of the two arms at the same end of the plate assembly are further connected as by means of a link 130 (see Fig. 13).

Associated with each arm is a pawl 131 pressed by a spring 132 so as to engage the associated ratchet wheel 125. The extension 127 which is disposed rearwardly of each arm 126 is provided with a plurality of holes 135 through any one of which a bolt 136 may extend to fasten thereto a head piece 133 from the opposite ends of which

are extended pins 134. Between these pins is an appreciable space wherein the rocker arms 1 may freely oscillate, the result being that first one pin and then the other is engaged thereby to effect a limited swinging movement of each arm 126. By properly adjusting the position of the head piece 133 an operative movement of the several pinions 115 and 116 may be assured. In this manner an intermittent rotation is imparted to all of the pinions 115 and 116 if the same be interconnected, as shown in Fig. 10, or to any selected group of pinions if the same be adjusted according to any of the suggested arrangements, as in Figs. 16 to 19 inclusive.

With the apparatus heretofore described, chromatic printing may be performed to obtain any of the color combinations suggested in Figs. 16 to 19 inclusive. In these I have represented certain sections of the form as covered with distinctive coloring, the surface shading indicating red, blue, black, and brown for convenient differentiation. The manner in which the printing operations are performed will now be explained.

Assuming that it is desired to print in four colors, the pinion arrangement suggested in Fig. 16 may be used. A quantity of ink is thereupon applied to each of the four blades two of which operate in conjunction with each inking roller, but along opposite end portions thereof. The travel of the carriage will result in the ink being transferred to the printing rollers, the two in the upper system each receiving two of the colors, but upon separate end portions thereof, and the two printing rollers in the lower system each receiving the two remaining colors, but along separated end portions thereof. These roller movements, however, do not effect any general distribution of the ink longitudinally of the printing rollers. This is accomplished by contact of the roller systems with the plate wherein are assembled the several pinions. By separating each of the four groups of two pinions in the manner suggested in Fig. 16, each set of two pinions will cooperate with only one end portion of one pair of printing rollers. As these pinions lie flush with the recessed plates wherein they are mounted, a contact of the printing rollers therewith will effect a distribution of ink along these rollers. By arranging the pinions in accordance with Fig. 16, there will be no longitudinal transfer of ink of one color to an area occupied by ink of another color. On the downward stroke of the carriage, an imprint in four colors will accordingly take place, each color being confined to a predetermined section of the form, as indicated. The form may thereafter be turned around 90, 180 or 270 degrees, as is

desired, and the work again be placed in the press so as to effect a four color print with a proper registration of each color.

A print of three colors may be made according to the arrangement suggested in Fig. 17. In this instance, the pinions remain connected as described for Fig. 16, but a single color may be spread over two of the form sections instead of applying a different color to each section. This would be accomplished by applying the same color of ink to the same ends of the inking roller of each system.

In Fig. 18 is shown an arrangement by which printing in two colors is performed. According to this the ink on the printing rollers in one system is distributed from end to end, while ink of a second color is distributed in the same manner along the printing rollers in the other system. This manner of distributing the ink is brought about by adjusting the four pinions in each horizontal row in intermeshing relation. Another arrangement by which two colors only are printed is shown in Fig. 19, but in this case each printing roller in the two systems receives along its opposite end portions a distinct color of ink which does not mix with the other, owing to the arrangement of the pinions which are so grouped as to be separated vertically in the middle of the plate assembly, as shown.

I would have it noted that a special advantage results from the use of pinions such as are incorporated in the assembly of the ink distributing plate. The peripheral edges of these pinions are not only irregular in contour, but intermesh also, when desired, thus aiding in the distribution of ink from one to another. This action is unlike that which would attend the use of disks having a smooth circular periphery where the tendency is for the ink to be crowded off upon the surrounding stationary surfaces.

In the apparatus heretofore described the supply of ink is carried adjacent the two roller systems and accordingly is moved with the carriage. A different arrangement, however, may, if desired, be employed. Figs. 14 and 15 suggest a modification, in that a recess 140 is provided in the plate whereon the distributing pinions are carried, this recess having an upstanding lip 141 which serves to retain a quantity of ink 142 in place. A roller 143 is arranged to dip into this supply of ink, the roller being fixedly mounted for rotation about an axis 144. This roller is furthermore so disposed as to receive contact from the printing rollers as the same are moved upwardly with travel of the carriage. In this manner ink is transferred thereto and then distributed thereover by means of the pinions heretofore described.

Except for the fact that this arrangement provides for the ink supply being carried in the plate assembly rather than adjacent to the roller systems, the construction is the same as that already described.

Figs. 20 to 23 set forth a construction of latch members by which the inking roller component of each roller system is automatically restored to operative relation with the other component. Since this differs only in respect of the special parts now to be described, the remaining elements are unchanged and bear reference numerals the same as those applied to the corresponding elements in the remaining figures. By the use of arrows, I have also indicated the direction of travel of the carriage at the moment that the parts assume the positions shown in the diagrammatic Figures 20 to 22 inclusive.

In carrying out the invention, a latch member 150 is shown as secured to the overhanging wall 71 of the inking roller component, this latch being in the form of a spring plate having a bend which provides a hook 151 adapted to engage the top carriage rail 22. The latch member extends upwardly beyond the hook, and, as shown, inclines slightly outwardly as at 152, then inwardly, as at 153, is then nearly upright, as at 154, and finally terminates in an outwardly inclined lip 155. With the latch member having some such characteristics as these, I employ a finger 156 pivoted to the upper edge of the distributing plate 105 as at 157, and arranged to present its acting end 158 in contact with the spring as the carriage approaches its upper limit of travel. The latch member just described takes care of the inking roller component in the upper roller system, and, as shown, is supplemented by two other exactly similar springs 159 which are connected with the inking roller component of the lower roller system. These latter latch members may be connected thereto the same as previously described, and are shown as each formed with an inwardly extending horizontal section 160, integral or otherwise, which brings the upper extension of each spring in operative alignment with a pivoted finger 156 one of which is mounted close to each end of the plate 105.

According to this construction all three latch members will operate together, but independently, the center one and the two end ones controlling, respectively, the inking roller components in the upper and lower roller systems. From Fig. 20, it will be noted that the latches may engage with the top rail 22, and then with continued upward movement of the carriage the several fingers will be displaced until, in the topmost position, they clear the spring sections 154 and drop into their normal horizontal positions

where they rest upon stops 161. With a downward movement of the carriage, the spring sections 153 are caused to engage the acting end of the fingers and be outwardly displaced thereby, the result being that all the latches are released simultaneously, or nearly so, from engagement with the top rail 22 permitting the inking roller component in each roller system to renew its operative relation with the other component.

It will be obvious, of course, that this invention includes many details which are susceptible of embodiment in forms other than those which have been described and shown. Changes or modifications within the limits of the appended claims are, therefore, in contemplation, and will be deemed as falling within the purview of this invention.

I claim:

1. The combination with a printing press having a carriage and a form, one movable with respect to the other, of a duplex roller system mounted on the carriage, the two components of the system being adapted for independent swinging movement about a common axis, means for supplying ink to one component of the roller system, and, at times, for transferring the ink therefrom to the other component of the roller system, and a printing roller included in the latter system adapted to deliver the ink to the form, substantially as described.

2. The combination with a printing press having a carriage and a form, one movable with respect to the other, of a duplex roller system mounted on the carriage, the two components of the roller system being movable independently of each other about a common axis, means for supplying ink to one component of the roller system, means for controlling the transfer of ink therefrom to the other roller system, and means for controlling the delivery of ink from the latter roller system to the form, substantially as described.

3. The combination with a printing press having a carriage and a form, one movable with respect to the other, of two independently operable duplex roller systems mounted on the carriage, the two components of each roller system being each independently movable about a common axis, means for delivering to one component of each system a supply of ink in two colors, means for transferring the two colors of ink from each of said components to the other component in the associated roller system, and means for delivering from the last named components to selected portions of the form the individual colors of ink, substantially as described.

4. The combination with a printing press having a carriage and a form, one movable with respect to the other, of a duplex roller system mounted on the carriage, the roller

system including two components each movable independently of the other about a common axis, and each provided with an inter-engaging roller whereby ink may be transferred from one component to the other, an ink supply associated with one component of the roller system, a printing roller included in the other component of the roller system, and means whereby the printing roller is caused to engage only with certain selected portions of the form, substantially as described.

5. The combination with a printing press having a carriage and a form, one movable with respect to the other, of a duplex roller system mounted on the carriage, a driving connection between the several rollers, means for imparting rotation to the rollers when relative movement takes place between 10 the carriage and the form, the roller system comprising two components each movable independently of the other, one component including a printing roller and the other an inking roller, means whereby the driving 15 connection to the inking roller is broken during each cycle of relative movement between the carriage and the form, means for restoring at will the driving connection to the inking roller, means for moving one 20 component of the roller system relative to the other whereby the inking roller is shifted to an inoperative position, means for effecting a return movement of the roller components to reestablish the inking roller 25 in operative position, means for delivering to the inking roller a supply of ink, the inking roller being adapted to transfer the ink therefrom to the printing roller, substantially as described.

30 6. The combination with a printing press having a carriage and a form, one movable with respect to the other, of a duplex roller system mounted on the carriage, the roller system including two components each movable independently of the other about a common axis, there being a printing roller in one component and an inking roller in the other, means for effecting a transfer of ink from one of these rollers to the other when 35 the two components are in one position, means for transferring ink from the printing roller to the form, and means for changing the relative positions of the two components whereby the transfer of ink therebetween is suspended, said last named means being operable when relative movement takes place between the carriage and the form, substantially as described.

40 7. The combination with a printing press having a carriage and a form, one movable with respect to the other, of a duplex roller system mounted on the carriage, the roller system including two co-axially mounted relatively movable components in one of 45 which is a printing roller and in the other an

inking roller, means whereby the printing roller is caused to engage with certain selected portions of the form, means for supplying to individual portions of the inking roller inks which differ in color, means for transferring such variously colored inks from the inking roller to individual portions of the printing roller, means for distributing each individual color of ink over a selected portion of the printing roller, and means whereby the printing roller is caused to engage with certain selected portions of the form to imprint thereon the desired colors of ink, substantially as described.

45 8. The combination with a printing press having a carriage and a form, one movable with respect to the other, of a plurality of independent duplex roller systems mounted on the carriage, each roller system including an inking roller, a printing roller, means for delivering to individual portions of each inking roller a supply of ink, the inking roller being adapted to transfer the ink thereon to individual portions of the printing roller, means for distributing over each individual portion of the printing roller the ink so transferred thereto, and means whereby the several printing rollers are caused to engage with certain selected portions of the form to apply thereto in accordance with a prearranged plan the ink contained on the individual portions of the printing rollers, substantially as described.

50 9. The combination with a printing press having a carriage and a form, one movable with respect to the other, of a supply of variously colored inks mounted on the carriage, means including a printing roller for transferring to certain selected portions of the form the individual colors of ink so mounted on the carriage, and means for distributing along different portions of the printing roller the various colors of ink so transferred thereto, said distributing means including a plate wheron is mounted a plurality of pinions each of which is adapted to engage with the roller, the pinions being adjustable in the plate to conform to the color scheme employed, and means for rotating the pinions to thereby effect a distribution of ink along the different portions of the printing roller, substantially as described.

55 10. The combination with a printing press having a carriage and a form, one movable with respect to the other, of an inking roller mounted in the carriage, means for applying to certain selected portions of the printing roller ink of a distinctive color, means for distributing along each such selected portion of the inking roller the ink so applied thereto, said means consisting of a pair of meshing pinions adjustably mounted relative to the inking roller and adapted to engage therewith, means for effecting a relative movement between the carriage and the

form and between the carriage and the pinions, and other means associated therewith for rotating the pinions, substantially as described.

- 5 11. Means for distributing ink comprising a plurality of plates, a mounting wherein the several plates are adjustably secured in a manner whereby each may be shifted toward or from the others, each plate having 10 on its working side a recess wherein is arranged a pinion which presents one face in substantially flush relation with the working side of the plate, in combination with a printing press having a carriage and a form, 15 means for effecting relative movement between the carriage and form and between the carriage and the ink distributing means, the carriage being provided with a printing roller adapted to engage with the several 20 pinions, and means for rotating the pinions whereby a distribution of ink is effected along the several portions of the printing roller with which the pinions engage, substantially as described.
- 25 12. Means for distributing ink comprising a plurality of grouped pinions, a mounting for each pinion group such that the same may be shifted with respect to the others, and means for rotating all of the pinions, in combination with a press having a carriage and a form, one movable with respect to the other, there being means also 30 for effecting a relative movement between

the carriage and the ink distributing means, the carriage being provided with a printing roller adapted to engage with the several pinion groups to thereby distribute the ink along the printing roller throughout the portions thereof engaged by each, substantially as described.

40 13. Means for effecting a distribution of ink comprising four plates, means wherein the plates are mounted adjustably each with respect to the others, there being formed in the working side of each plate a recess, a 45 pair of pinions mounted in the recess of each plate and adapted to mesh with the pinions in the proximate plates when the same are adjusted suitably for this purpose, all of the several pinions being disposed in substantially flush relation with the working face of the plate, in combination with a press having a carriage and a form, one movable with respect to the other, the carriage and distributing means being also movable with 50 respect to each other, means for effecting such relative movement, other means associated therewith for imparting rotation to the several pinions in the ink distributing means, and a printing roller associated with the 55 carriage adapted to be moved across the several pinions whereby the ink on the printing roller is distributed lengthwise thereof with rotation of the pinions, substantially as described.

H. A. AGRICOLA, JR.
